UNITED STATES PATENT OFFICE.

LEO ROSENMAN, OF BROOKLYN, NEW YORK, ASSIGNOR TO R. K. M. MFG. COMPANY, A CORPORATION OF NEW JERSEY.

MACHINE FOR SEWING SEAMS WITH GAPS.

1,238,438.

Specification of Letters Patent. Patented Aug. 28, 1917.

Application filed September 3, 1914. Serial No. 859,951.

To all whom it may concern:

Be it known that I, LEO ROSENMAN, a citizen of the United States, residing at 882 Lafayette street, Brooklyn, county of Kings, 5 and State of New York, have invented certain new and useful Improvements in Machines for Sewing Seams with Gaps, fully described and represented in the following specification and the accompanying drawings, forming a part of the same.

The object of this invention is primarily to furnish a means of seaming strips together with gaps in the seam to admit metal fasteners, as hooks and eyes, which may 15 then be secured in the gaps by a row of stitching at the rear ends of the fasteners.

Such strips, provided respectively with hooks and eyes, or equivalent metal fasteners, are thus adapted for attachment to the 20 openings of garments for closing such openings detachably.

The invention may be used for other purposes to which it is adapted, and different parts of the invention may be used with or 25 without the other parts described herein.

The gaps in the line of stitching are formed by disposing a fold upon one of the strips along the sewing-line upon the other strip, along which line the seam or row of 30 stitches is extended, and is diverted when a gap is to be formed, outside the edge of the fold so as to pass through only one of the fabric strips. There is, therefore, no connection between the strips at such gap, and 35 space is thereby left to insert the metal fastener between the strips.

To strengthen the seam at the opposite ends of the gap, it is preferably reinforced by means of tie-strokes or tacking or extending several stitches across the line of 40 the seam at the beginning and end of the gap.

The sewing machine for performing these operations must therefore be adapted to automatically arrest or shorten the feed at 45 pairs of adjacent points upon the sewing-line, which points are to form the ends of the gap, and means must be provided when the feed is thus arrested to extend the 50 stitches laterally transverse to the sewing-line, to reinforce the seam.

A machine for making either zigzag or straight-line stitches may be employed; if the zigzag or embroidery machine be used 55 the mere arresting or shortening of the feed

will operate to form stitches across the line of the seam, to reinforce the ends of the gap as desired; but if a straight-line machine be used, means must be provided to shift the needle or the cloth back and forth across 60 the line of the seam, to form the tie-stitching or reinforcing stitches of the cloth fabric.

Where the shifting of the cloth is necessary, provision is made for lifting the foot 65 to clear the cloth from the feed-dog, during such shifting operation, and the shifting itself is conveniently effected by a scroll or cloth-guide attached to the foot, so that the oscillation of the foot will shift the cloth transversely beneath the needle.

An embodiment of the invention is shown in the annexed drawing, but it will be readily understood from the following description that the invention does not consist in the precise mechanism shown herein, 75 but broadly in the means for performing mechanically and automatically the successive operations required in seaming the strips together with gaps in the seam to receive metal fasteners.

The invention will be understood by reference to the annexed drawing, in which Figure 1 is an elevation of the rear side of a sewing-machine provided with the improvements; Fig. 2 is a front elevation of the machine; Fig. 3 is a plan of the machine; Fig. 4 is a plan of the foot and cloth-guide with a portion of the seamed cloth; Fig. 5 is a portion of the seamed strip with two eyes secured thereon; Fig. 6 is an elevation of 80 the cam-slide which operates upon the feed; Fig. 7 is a cross section on line 7-7 in Fig. 1; Fig. 8 shows a strip with eyes inserted; Fig. 9 is a section on line 9-9 in Fig. 4; and Fig. 10 a section on line 10-10 in Fig. 95. Fig. 11 is a plan showing the duplication of the cloth-guides upon the presser-foot, to be used with two needles.

The frame of the machine is shown with bed A, standard B, goose-neck C, needle-bar D, and foot-bar E, carrying foot F and cloth-guides G and G'.

The needle-bar is reciprocated by suitable connections to a driving-shaft H, and the auxiliary attachments employed for the 105 present invention are operated by a cross-shaft I supported in bearings J, J' upon the under side of the goose-neck with cams to arrest the feed, and for lifting the foot and for oscillating the foot.

110

This cam-shaft has three cams rotated by a worm-wheel α and a worm β upon the driving shaft. The worm-wheel advances one tooth for each reciprocation of the needle, and the number of teeth in the worm-wheel is equal to the number of stitches required to perform one cycle of the desired operations.

The foot is attached to a foot-bar E which is movable in bearings in the head C' of the machine parallel with the needle-bar D . Arms e are projected from the foot-bar above and below its bearings and carry a rocker-bar d to which a connection is made from a cam I , to oscillate the foot-bar, the foot, and the cloth-guide.

The cam I has certain projections which operate to oscillate the foot and cloth-guide by means of a rocker-bar d and a link-rod d' having a spring d'' to retract it. The head of rod d' is fitted movably to the body-rod d . The cam is formed as a disk with three projections e , e' , e'' , which operate as follows:

When the feed is stopped or greatly reduced, to permit the angularly disposed tie-stitching or reinforcing of the seam at the beginning of a gap, the sloping end of the projection e presses upon the link-rod and moves the cloth-guide so that a stitch is taken transversely to the sewing-line.

The top of the projection e holds the cloth-guide stationary while the needle is in the cloth, and when the needle is withdrawn from the cloth, the continued rotation of the cam permits the second sloping portion of this projection to clear the end of the link-rod, which can then rest upon the edge of the cam between the projections e and e'' , and produces a second stitch across the sewing-line and brings the stitch again upon the edge of the strip n .

The first end of the central projection e'' operates before the feed is again started, to produce another oscillation of the cloth-guide, during the formation of a third cross-stitch, which brings the stitching off of the strip n .

The feed is re-commenced at the conclusion of the three reinforcing stitches, and the top of the cam e' is made of sufficient length to hold the cloth-guide stationary, while three stitches are formed off the edge of the strip n , to make the desired gap.

The feed is stopped upon the completion of these three stitches, and the end of the projection e' , when it moves clear of the link-rod d' , permits the spring d'' to move the cloth guide so as to produce a tie-stitch or cross-stitch at the end of the gap, angularly to and preferably at right-angles to the sewing-line.

The projection e'' then operates upon the cloth-guide the same as the projection e , to produce two more transverse stitches while

the feed is arrested, and the concentric surface of the cam then holds the cloth-guide to form the stitching along the edge of the strip n until the feed is arrested to form another gap.

With the cam shown in the drawing, such concentric surface permits the formation of twenty-one stitches between the gaps, which with the three reinforcing stitches at each end of the gap and the three stitches beyond the edge of the strip n , makes thirty stitches in all; and such a cam is easily designed by dividing its periphery into thirty parts and making the projections of suitable length and at suitable spaces upon the edge of the cam.

With such a cam, a worm-wheel having thirty teeth would be used, so as to turn the cam once for each thirty stitches of the needle.

Fig. 4 shows the two strips m and n to carry the metal fasteners, the former serving as a base which may be made of any width for attachment to the garment-opening, and the latter having a fold m' at one edge, which fold is secured to the base by a line of stitches o .

Intermediate to the projections e and e' , a projection e'' of much greater length is provided, to hold the foot and cloth-guide to one side of the sewing-line while several stitches are made, thus clearing the fold upon the edge of the strip n , which is elsewhere united to the base m .

Fig. 4 shows at o' the stitches made while the cloth-guide is held at one side of the sewing-line o and which clear the edge of the fold n' , thus leaving such fold disconnected from the base.

o'' shows the tie-stitching or cross-stitches for reinforcing the ends of the gap p .

Fig. 5 shows fasteners in the form of metal hooks inserted in the gaps which are thus formed, and which are lettered p in Fig. 4.

Figs. 2 and 4 show a wide cloth-guide G attached to the foot F to guide the base-strip m beneath the needle, and also a cloth-guide G' adapted to guide the narrower strip n and to make folds n' at its opposite edges.

The strip n is sewed upon the base m with the fold n' exposed, so that when the strip is folded over upon the base as in Fig. 5, the folds of the strip n are concealed.

Fig. 9 shows, in section, the strip n secured upon the base-strip m by stitches o , and Fig. 8 shows the strip n folded over, as in Fig. 5, in which position it may be secured behind the eyes by a line of stitching q , when attached to the garment.

During the oscillation of the foot, it is desirable to lift the same to remove the cloth from pressure upon the feed-dog, and such lifting is effected by cam-faces l which

are formed upon blocks L' on the inner side of the disk of the cam L, which cam-faces operate upon the rear end f of a lever f' which is pivoted upon the goose-neck at h, 5 and its forward end fitted beneath the arm e upon the upper end of the foot-bar E. When lifted, the rod d slides through the head of the bar d'.

The foot-bar is, in practice, pressed normally downward by a spring, and therefore 10 presses the cloth upon a feed-dog e' with the desired force, and the lifting-lever f' may be engaged with the foot-bar in any desired manner to lift the same.

15 To lift the foot and to oscillate it in the proper relation to the gaps required upon the seam, the cams are made to rotate once during each complete cycle of operations required to make one gap and connect it by 20 a line of stitching with that previously made. Such rotation of the cams is shown effected by a worm-wheel a and worm b, and the number of teeth in the worm-wheel may be varied to produce the desired relation, or the cams may be rotated by other means.

To arrest or shorten the feed at the points where the tie-stitching or reinforcement of the gaps is desired, a connection is made between the driving-shaft H and the feed adjusting shaft r (see Figs. 1 and 6), which is 30 connected with the shaft s by which the feed-dogs are moved.

The shaft r is manually operated in such 35 cases by a finger-lever r', and the novelty of the present construction consists in connecting the driving-shaft H by a cam with the feed-shaft r, so that the rock-shaft may be actuated automatically at suitable intervals 40 to arrest the feed at each end of the gap.

For this purpose, a slide M is fitted to a dove-tail upon the bearing J', as shown in Figs. 3, 5 and 6, and connected by a rack s' and a pinion s² to move the feed-shaft.

45 A cam N is fitted to the cam-shaft I outside of such slide, and the latter is provided with a roll N' which is held against the edge of the cam by a spring N².

A screw N³ is attached to the bottom of 50 the bearing J' to bear upon a shoulder upon the bottom of the slide.

The upper and lower edges of the cam N are indicated in dotted lines in Fig. 6, and two adjacent projections n³ are formed upon 55 the edge of the cam to reduce the feed twice in such cam rotation, at the ends of a gap. The roll N' is shown in Fig. 6 in position when the second stitch at the side of the gap is being formed.

60 Each of the projections n³ reduces the feed to permit the reinforcing with three stitches at one end of the gap.

The cam being rotated once by the worm-wheel for a definite number of stitches, the 65 feed is thus automatically shortened or ar-

rested at the proper points in the sewing-line, to form a gap of the desired length.

The screw N³ is provided to regulate the stroke of the feed, as this screw determines the extent to which the slide shall move 70 downward after it is lifted by the cam-projections n³.

The transverse length of the stitches across the sewing-line may be varied by the adjustment of a collar d³ upon the link-rod d', 75 which collar contacts with one of the bearings of the rod when the cam-projections e, e', e² have moved it, and thus determines the extent of retraction effected by the spring.

80 It will be understood that the machine has means for moving the cloth and needle in relation to one another transversely or angularly to the sewing-line, and means for varying the extent of such transverse movement, 85 and also possesses means for lifting the foot during such transverse movement to clear the fabric-strip from the feed-dog.

The machine also has means in the cam N and its connections to the rock-shaft r, for 90 automatically shortening or arresting the feed at definite points, thus securing, with the transverse movement, means for repeating the stitches at such points to reinforce the seam at the ends of the gaps. Such 95 "shortening" or "arresting" I have termed "reducing" in the claims.

The product of this machine is made the subject of a separate application No. 856,397 filed by me August 12, 1914, with title, Gar- 100 ment-fastener holder, but the product is fully illustrated herein.

Great economy of manufacture is secured by using a machine with two needles to form hook and eye strips simultaneously. In 105 Figs. 1, 2 and 4, the foot F is shown with the cloth-guides G and G' adapted to guide the base-strip, and the machine may be provided with two needles and such guides doubled, to feed hook-strips and eye-strips separately to the needles, and thus secure perfect coincidence of the gaps upon both strips.

Fig. 11 shows a foot F' provided with two sets of guides, one being wide to receive hooks in the gaps, and the other being much 115 narrower to receive eyes in the gaps, as it is common to use much narrower strips for the application of eyes to a garment.

The foot is provided with slots t and t' for the passage of needles u and u', and is 120 also provided opposite the needle u with wide guides G, G', and upon the other side with narrow guides g, g'.

The two products are shown moving side by side from the needles with the gaps in 125 the sewing-line exactly coincident.

The strips with the hooks and eyes se- cured in the gaps may be called "garment- 130 fastener holders," and these holders are not only made to agree perfectly with one an-

other by the means described, but are produced with much greater rapidity than if made in separate operations, while also adapting them more perfectly for co-operative use.

Where the duplicated fixtures are attached to the foot, all the operations of the machine are the same as described herein in connection with the cloth-guides G, G' alone, as 10 the formation of the seam and the reinforcing gaps are similarly produced by each of the needles.

I have made claim herein to combinations of means for performing the operations 15 which are effected in the machine shown and described herein; but it is obvious that any equivalent means may be used without departing from my invention, which is not therefore limited to the particular construction shown herein.

It is immaterial whether a foot and cloth-guides constructed to oscillate upon a foot-bar be used, or a foot and cloth-guides mounted to slide transversely of the sewing 25 line, as both would operate in the same manner to move the cloth transversely to such line.

It is immaterial whether the feed is arrested or sufficiently shortened in making the 30 gap and reinforcing the seam at the ends of the gap, as it is common to greatly reduce the feed in sewing machines, which would enable the needle to lay several stitches close to one another across the sewing-line, and 35 thus produce the desired reinforcement.

Where a zigzag machine is used, means must be provided not only to arrest or greatly shorten the feed, but also to wholly arrest the vibrations of the needle, as otherwise 40 the stitches would reach the line of the seam at each vibration of the needle and no gap would be formed.

I claim:

1. In a sewing machine, mechanism for 45 sewing a plurality of strips together with a seam provided with gaps to receive fasteners, a reciprocating needle, a feeding means, a plurality of superposed guiding devices, each device being employed for guiding a 50 strip of fabric, and means actuated by the machine for moving said guiding devices laterally relative to the main sewing line and holding said devices in each of a plurality of different lateral positions for a 55 plurality of stitches, in one of said positions one of said guiding devices having its delivery end out of alignment with the line of stitching.

2. In a sewing machine, mechanism for 60 sewing two strips together with a straight seam, which consists of a reciprocating needle, a feeding means, and cloth-guides for feeding said strips beneath the needle and to said feeding means, an oscillatory bar carrying 65 said cloth-guides, and means co-operating

with said bar for swinging said cloth-guides so as to move the strips transversely of the sewing line and to produce reinforced stitching transversely to said straight seam.

3. In a sewing machine, the mechanism 70 for seaming two strips together with gaps in the seam to receive metal fasteners, which consists of a reciprocating needle, feeding means for feeding said strips beneath the needle to form a straight seam along the 75 edge of at least one of the strips, means for reducing the feed at pre-determined points and repeating the stitching back and forth at such points to provide tie-strokes and reinforce the seam at said points, and means 80 for shifting the entire strip to hold its edge clear of the needle and forming thereby a gap in the line of stitches with a row of stitching in front of the gap at one side of the line of the seam.

4. In a sewing machine, the mechanism 85 for seaming two strips together with gaps in the seam to receive metal fasteners, which consists of a reciprocating needle, feeding means for feeding said strips beneath the 90 needle to form a straight seam along the edge of at least one of the strips, cloth guides adapted to guide the strips, means to shorten or arrest the feed at pairs of the adjacent points in the sewing line, means to 95 laterally shift the guiding edge of the cloth guides several times back and forth and angularly to and from the sewing line at the points where the feed is reduced to provide tie-strokes and reinforce the seam at the 100 said points.

5. In a sewing machine, the mechanism 105 for seaming two strips together with gaps in the seam to receive metal fasteners, which consists of a reciprocating needle, feeding means for feeding said strips beneath the 110 needle to form a seam along the edge of at least one of the strips, cloth-guides adapted to guide the strips, means to shorten or arrest the feed at pairs of adjacent points 115 in the sewing line, means to laterally shift the guiding edge of the cloth-guides several times back and forth and angularly to and from the sewing line at the points where the feed is reduced to provide tie-strokes and reinforce the seam at the 120 said points, and means for holding the cloth-guides stationary in their laterally shifted position between the adjacent points, and for feeding and stitching the cloth at one side of the seam between such adjacent points while in such shifted position.

6. A sewing machine having a driving-shaft and means connected thereto and operating in unison, such means consisting of 125 a needle-bar, means for reciprocating the same, means for feeding material to the needle, means for reducing the feed at pre-determined points, a foot having a cloth-guide and a foot-bar, and bearings in which 130

the bar may oscillate, and means to oscillate the bar when the feed is reduced, to oscillate the cloth-guide transversely to the sewing-line.

5. 7. A sewing machine having a driving-shaft and means connected thereto and operating in unison, such means consisting of a needle-bar, means for reciprocating the same, means for feeding material to the 10 needle, a slidable foot-bar, and a foot attached thereto, bearings in which the foot-bar may oscillate and reciprocate, a cloth-guide attached to the foot to direct the cloth, means to reduce the feed at adjacent fixed 15 points, means to oscillate the foot when the feed is reduced, means to reinforce the seam at the fixed points, and means to lift the foot during such oscillation.

8. A sewing machine having means to 20 reciprocate a needle, a foot having a cloth-guide attached thereto, means to lift and move the foot transversely and across the sewing line, a feed dog, a cam, and manually controlled means between said feed-dog and 25 the cam to vary the feed, and means operating automatically to reduce the feed at definite points upon the sewing-line.

9. A sewing machine having a driving shaft, a needle-bar reciprocated by said 30 shaft, means for feeding the material to the needle, a foot-bar mounted to rock in bearings parallel with the needle-bar, a foot carried by the foot-bar with a cloth guide attached thereto, means to lift the foot, and 35 means actuated by the driving-shaft to rock the foot-bar at intervals and oscillate the cloth-guide transversely to the sewing-line when the foot is lifted.

10. A sewing machine having a driving- 40 shaft, a needle-bar reciprocated by said shaft, means for feeding the material to the needle, a foot-bar mounted to rock in bearings parallel with the needle-bar, a foot carried by the foot-bar with a cloth-guide at- 45 tached thereto, a worm upon the driving-shaft, a worm-wheel rotated thereby, and a cam rotated with the worm-wheel and having projections operating to rock the foot-bar at definite intervals and thereby 50 shift the cloth-guide transversely to the sewing-line.

11. A sewing machine having a driving- 55 shaft, a needle-bar reciprocated by said shaft, means for feeding the material to the needle, a foot-bar mounted to rock in bearings parallel with the needle-bar, a foot carried by the foot-bar with a cloth-guide

attached thereto, a worm upon the driving-shaft, a worm-wheel rotated thereby, two cams driven by the worm-wheel, and op- 60 erated, one to lift the foot at pre-deter- mined intervals, and the other to rock the foot-bar and foot when thus lifted.

12. A sewing machine having a driving-shaft, a needle-bar reciprocated by said shaft, a feed dog having a connection to the driving-shaft for arresting or varying its move- 65 ment, a foot-bar mounted to rock in bear- 70 ings parallel with the needle-bar, a foot and cloth-guide carried by the foot-bar, a worm upon the driving-shaft, a worm-wheel ro- 75 tated thereby, and cams rotated with the worm-wheel and operated, one to lift the foot at pre-determined intervals, another to rock the foot-bar and cloth-guide when thus lifted, and the other to arrest the feed at corresponding intervals.

13. A sewing machine having a driving- 80 shaft and means to reciprocate a needle to sew a seam, a foot-bar mounted to rock or turn in bearings, a foot carried by the foot- 85 bar with a cloth-guide attached thereto, means connecting the driving-shaft with such foot-bar for automatically turning the foot-bar, and means for varying the extent 90 of such turning or rocking motion, sub- stantially as herein set forth.

14. A sewing machine having a driving- 95 shaft and means to reciprocate a needle, means for feeding the cloth, a feed-adjust- 100 ing shaft with means for manually varying or arresting the feed, means connecting the driving-shaft with the said feed-adjusting shaft for automatically reducing the feed at definite intervals, and means connected 105 therewith for varying the extent of the feed.

15. In a sewing-machine, a foot, a driving shaft and means connected thereto and operating in unison therewith, such means con- 100 sisting of mechanism for reciprocating a needle, means for feeding the cloth, means for reducing the feed at intervals along the sewing line, means for producing tie-strokes angularly to the seam along the sewing line and thereby reinforcing the same thereat, 105 and means for holding the foot in a shifted position while producing the tie-strokes.

In testimony whereof I have hereunto set my hand in the presence of two subscribing witnesses.

LEO ROSENMAN.

Witnesses.
